[57] ABSTRACT

A process for producing valuable products including gasoline and jet fuel by catalytic cracking with an acidic catalyst wherein the catalyst activity is improved and the selectivity of the catalyst for production of various C₅+ product cuts is increased by carrying out the catalytic cracking process in the presence of dispersed carbon particles added to the reaction zone. Preferably, the particles are added to the hydrocarbon feedstock and dispersed therein prior to contacting the feedstock with the catalytic cracking catalyst in the reaction zone.

CATALYTIC CRACKING PROCESS USING EXTERNALLY INTRODUCED CARBON PARTICLES

CROSS-REFERENCE TO RELATED APPLICATIONS

This application is a continuation-in-part of U.S. application Ser. No. 372,118, filed June 21, 1973, now abandoned, the disclosure of which is hereby incorporated by reference.

BACKGROUND OF THE INVENTION

The ever-growing demand for crude oil coupled with the diminishing supplies has created an energy crisis. In view of the present situation, the necessity for squeezing the maximum amount of energy out of each barrel of crude is obvious.

This invention is directed to a process for improving conventional catalytic cracking processes to more closely approach that optimum.

DESCRIPTION OF THE PRIOR ART

The use of activated carbon, a highly active, non-acidic catalyst, for cracking of hydrocarbons is not new. See, for example, the article titled "Catalytic and Thermal Cracking of Pure Hydrocarbons" appearing in the November 1949 issue of Industrial and Engineering Chemistry. The combination, however, of carbon particles with a conventional acidic cracking catalyst in the method described hereinafter is believed to be new.

SUMMARY OF THE INVENTION

The subject invention is directed to cracking of a hydrocarbon feedstock in a catalytic cracking zone by contact with an acidic cracking catalyst in the presence of carbon particles which have been either added to the hydrocarbon feedstock prior to introduction of the feedstock into the catalytic cracking zone or have been introduced into the catalytic cracking zone concurrently with the hydrocarbon feedstock. Preferably, the carbon particles are added to the hydrocarbon feedstock and suspended therein. The carbon particles, preferably in the form of petroleum coke or charcoal, are dispersed in the feedstock in an effective amount generally ranging from 0.1 to 10, preferably 0.5 to 7 weight percent, based on the combined weight of the feedstock and the carbon particles.

DETAILED DESCRIPTION OF THE INVENTION

As discussed above under "SUMMARY OF THE INVENTION", the subject invention is directed to a process for catalytically cracking a hydrocarbon feedstock in the presence of dispersed carbon particles purposely added to the reaction zone. By the process of this invention, increased gasoline and jet fuel yields, without the concurrent increased gas yield normally attributed to increased conversion levels, may be obtained. Additionally, the activity of the catalyst is improved.

The process of this invention utilizes conventional hydrocarbon feedstocks to catalytic cracking zones, conventional acidic catalytic cracking catalysts, and conventional catalytic cracking conditions. This invention is directed to the improvement of carrying out the catalytic cracking process step in the presence of externally introduced carbon particles; that is, in the presence of carbon particles which have been either (1) purposely dispersed in the hydrocarbon feedstock prior

to contacting said feedstock with the catalytic cracking catalyst, or (2) have been purposely introduced into the catalytic cracking zone concurrently with the introduction of the hydrocarbon feedstock to the catalytic cracking zone.

By the process of the subject invention, as will become clear by consideration of the examples, catalyst activity is increased and the selectivity of the catalyst for producing various C₅+ (defined as hydrocarbons having five or more carbon atoms) product cuts is increased.

CATALYTIC CRACKING CATALYSTS

The acidic catalysts used in the catalytic cracking zone in the process of the present invention are those conventionally utilized in catalytic cracking processes. For example, activated, naturally occurring acidic catalytic cracking catalysts such as clay, i.e., kaolin, can be used. Synthetically prepared acidic cracking catalysts containing amorphous silica-alumina, with or without additional promoters, can also be used, as well as semi-synthetic catalysts such as kaolin-silica-alumina composites. Zeolite-containing catalysts may also be used to reduce coke formation on the catalyst particles and to increase catalyst activity. Methods of preparation of amorphous catalytic cracking catalysts are well known. The crystalline zeolitic molecular sieve catalysts are disclosed and discussed in great detail in U.S. Pat. Nos. 3,210,267 and 3,271,418.

It should be recognized that different hydrocarbon feeds to the catalytic cracker present different problems and the catalyst used will in general be tailored to fit the particular needs of the hydrocarbon feedstock being used.

OPERATING CONDITIONS IN THE CATALYTIC CRACKING ZONE

The temperature of the inlet of the catalytic cracking zone will generally fall within the range from about 400° to about 1250°, more preferably 850° to 1100°, with a conversion level of from 40 to 90% on a volume basis. The pressure within the zones will generally fall within the range from about 1 to about 100 psig, preferably 5 to 25, more preferably 15 to 20. The liquid hourly space velocities within the catalytic cracking zone will generally fall within the range from about 0.5 to about 50, although it can be as high as 100 or even higher. More generally, the space velocity within the catalytic cracking zone will fall within the range from about 2 to about 20. The preferred temperatures for use in the catalytic cracking zone will generally fall within the range from about 850° to about 1050°, preferably 925° to 975°.

The catalytic cracking of the present invention may be performed utilizing well-known techniques, including, for example, fluidized bed or moving bed processes. Regeneration of the catalyst can be carried out using conventional regeneration techniques.

The hydrocarbon feedstock useful in the present invention will generally boil above about 400°, preferably in the range from about 450° to about 1000°; and more preferably 600° to 1000°. The hydrocarbon feedstocks may include, for example, light and heavy gas oils obtained from atmospheric distillation, vacuum distillation and coker gas oils. The reaction conditions can be adjusted in the cracking zone according to the conversion level desired.

Carbon particles, as noted above, are preferably introduced into the feedstock by dispersion therein prior to introduction of the feedstock into the catalytic cracking zone. The carbon particles preferably are suspended in the feedstock in an amount of 0.1 to 10 percent by weight, preferably 0.5 to 7 percent by weight, based on the combined weight of the hydrocarbon feedstock and carbon particles. Alternatively, as pointed out above, they may be introduced directly into the catalytic cracking zone concurrently with the introduction of the hydrocarbon feedstock. The size of the carbon particles will generally lie in the range of 40-90 microns. The quantity of carbon particles used within the general range specified above will vary dependent on the feedstock, nature of the carbon particles, operating conditions and desired products. Petroleum coke and activated carbon, particularly that derived from coconuts, are particularly desirable carbon sources.

It should be noted that coke buildup on an acidic catalyst utilized in conventional catalytic cracking processes occurs during the process operation. The subject invention utilizes discrete carbon particles introduced from an external source. The coke buildup occurring on the acidic catalyst particles serves to decrease cata-

5 was carried out in a fixed bed using a standard 5-minute cracking cycle. Various quantities and types of carbon particles were combined with the feedstock prior to contacting the feedstock with the catalyst, as indicated in Table II. A liquid hourly space velocity on a weight basis of 3 was used for all runs. The results are shown in Tables II and III.

TABLE I

FEEDSTOCK - HEAVY GAS OIL

4	(5) coke	0.5	923	60.6	21.4	21.6	35.1	23.8
5	(5) coke	5.0	911	62.0	25.7	22.2	38.1	25.5

(1) Added to feedstock based on combined weight of particles and feedstock.

(2) On weight basis to materials boiling below 500°F., i.e., (weight of 500°F. product ÷ weight of feed) × 100.

(3) Wt. % of this particular product to fresh feed, (not including carbon particles added to feed).

(4) Activated coconut charcoal with a surface area of greater than 80 m²/g.

(5) Petroleum coke with a surface area of 1-10 m²/g.

lyst activity, while the carbon particles introduced into the system by the process of the subject invention increase catalyst activity and selectivity, as noted in the 45 following examples, which are offered by way of illustration and not by way of limitation.

EXAMPLES

A catalytic cracking catalyst in the form of pills of 20 to 32 mesh size and having a surface area of about 77 m²/gram, Y-zeolite content of about 12 weight percent, a density of about 0.8 gm/ml, and a silica-alumina weight ratio of about 32:48, was used to crack a feedstock having the inspection set forth in Table I. The test

50 As can be seen from the data set forth in Table II, the catalytic cracking catalyst used in conjunction with 6.6% charcoal in the feedstock gave an 82.7% conversion rate at a catalyst temperature of 904°F. This is in contrast to the conversion level of 68.3% at 927°F. for the same catalyst without the addition of carbon particles to the feedstock. The product distribution and quantities was also higher for the coke containing feedstock. Coke was not as effective in increasing catalyst activity. However, the coke was effective in increasing middle distillate yield.

The amount of gas produced and its analysis for each of the five runs is shown in Table III.

TABLE III

RUN NO.	1	2	3	4	5
<u>Gas Analysis</u>					
<u>Wt. % to Fresh Feed⁽¹⁾</u>					
Methane	1.15	0.68	1.02	0.96	0.99
Carbon Dioxide	0.39	0.08	0.08	0.09	0.25
Ethylene	0.78	0.52	0.53	0.40	0.65
Ethane	1.00	0.53	0.54	0.69	0.82
Propylene	4.32	2.40	1.95	2.49	2.53
Propane	1.66	1.46	0.93	1.13	1.71
Isobutane	4.20	3.47	3.38	2.02	2.53
Isobutene	2.05	1.13	1.12	1.41	1.82
N-butane	1.05	0.59	0.58	0.33	0.45

5
TABLE III -Continued

RUN NO.	GAS YIELDS				
	1	2	3	4	5
Cis-2-Butene	0.72	0.52	0.59	0.50	0.67
Trans-2-Butene	1.01	0.73	0.82	0.71	0.95
Total ⁽²⁾ C ₄ -	18.33	12.11	11.54	10.73	13.37
Wt. % to Fresh Feed					

⁽¹⁾ "Fresh feed" does not include carbon added thereto.

⁽²⁾ "C₄-" means hydrocarbon gases having four or less carbon atoms.

As can be seen from Table III, the amount of gas produced was dramatically lower using the process of this invention.

The conversion of the feedstock to olefinic materials is shown in Table IV.

TABLE IV

Run	Ratio ⁽¹⁾	C ₃ = Wt. % ⁽²⁾	Ratio ⁽¹⁾	C ₄ = Wt. % ⁽²⁾
1	72.2	4.32	42.0	3.78
2	62.1	2.40	37.0	2.4
3	67.8	1.95	39.1	2.5
4	68.8	2.49	52.8	2.62
5	59.6	2.53	53.6	3.44

⁽¹⁾ Ratio equals weight of olefin $\times$ 100 / (weight of olefin plus weight of paraffin with same number of carbon atoms)

⁽²⁾ Wt. % olefin to fresh feed.

As can be seen from Table IV, the yield quantities of C₃ + C₄ olefins are reduced by the selectivity of the catalyst being shifted to heavier hydrocarbons boiling in the gasoline range.

It is apparent that many widely different embodiments of this invention may be made without departing from the scope and spirit thereof; and, therefore, it is not intended to be limited except as indicated in the appended claims.

What is claimed is:

1. In a process wherein a hydrocarbon feedstock is catalytically cracked by contacting said feedstock with an acidic catalytic cracking catalyst in a catalytic cracking zone, the improvement which comprises cracking said feedstock in the presence of an effective amount of dispersed carbon particles added to said reaction zone.

2. The process of claim 1 wherein said carbon particles are added to said feedstock and dispersed therein prior to contacting said feedstock with said acidic catalytic cracking catalyst.

3. The process of claim 1 wherein said carbon particles are introduced into said catalytic cracking zone concurrently with said hydrocarbon feedstock.

4. The process of claim 1 wherein said carbon particles are present in an amount of from 0.1 to 10 weight percent based on the combined weight of said feedstock and said carbon particles.

5. The process of claim 1 wherein said carbon particles are present in an amount of from 0.5 to 7 weight percent based on the combined weight of said feedstock and said carbon particles.

6. The process of claim 1 wherein said carbon particles are petroleum coke.

7. The process of claim 1 wherein said carbon particles are activated charcoal.
